UNITED STATES PATENT OFFICE

EDWARD E. KLEINSCHMIDT, OF PARK RIDGE, ILLINOIS, ASSIGNOR TO TELETYPE CORPORATION, OF CHICAGO, ILLINOIS, A CORPORATION OF DELAWARE

PRINTING TELEGRAPH

Application filed November 11, 1925, Serial No. 68,307, now Patent No. 1,811,132, dated June 23, 1931, which is a continuation of application Serial No. 656,857, filed August 11, 1923, Patent No. 1,567,599, dated December 29, 1925. Divided and this application filed January 22, 1931. Serial No. 510,537.

The present invention pertains to improvements in selective mechanisms especially adapted for printing telegraphs, but applicable to other uses.

5 This application is a division of prior application Serial No. 68,307, filed November 11, 1925, now Patent No. 1,811,132, June 23, 1931, and in the specific embodiments disclosed relates particularly to improvements in printing telegraph shift control mechanisms.

10 It is general practice to provide stock tickets that record in offset lines upon a wide tape; the letters case characters being recorded on the upper line and the figures case characters being printed on the lower line. The recording of stock designations and quotations results in many more changes from letters to figures and from figures to letters than occurs in ordinary telegrams. In message work, permutation code printers use special code permutations for the shifting operation. If the same method is used for stock tickers the speed of the operator is greatly reduced, and the number of impulses to be transmitted over the line greatly increased; and the transmitting capacity in characters much reduced.

15 In the specific embodiments of the present invention an impulse or case selecting condition is added to the five selecting conditions ordinarily used in printers using the Baudot type of permutation code, and the added condition is used to determine whether the character is a letter or figure. By this means all special shift operations are eliminated on the part of the operator thus materially increasing the speed and accuracy of operation, and a smaller number of line impulses are required to transmit the same number of characters thus increasing the number of characters which can be transmitted in a given circuit.

20 The primary object of the present invention thus is to provide means for printing in offset lines without using code permutation signals for case selecting operations or shifting by adding to the character selecting impulses of each signal a shift or case selecting condition, the effect of which is to determine

whether a letter case character or a figure case character is to be recorded.

25 This invention further provides a shift or case control mechanism whereby characters of one group may be recorded successively until a character signal of another group is received, the reception of which character will cause the shifting operation and printing operation to be accomplished concurrently.

30 Another object is to provide entirely mechanical shift control mechanisms whereby the printing and shifting operations can be performed simultaneously, and in which the shifting mechanism remains quiescent 60 during the printing of successive characters in either one of two groups of characters.

35 Still further objects of the invention will appear hereinafter in the detailed disclosure of preferred embodiments of the invention 70 and are such as may be attained by utilizing the various combinations and sub-combinations hereinafter set forth and as defined by the terms of the appended claims.

40 Referring to the drawings: 75 Figure 1 is a fragmentary sectional elevation showing one form of shift mechanism involving the principles of the invention.

100

Since the subject matter in the present case is a division of co-pending application 68,307, filed November 11, 1925, which is a continuation of the subject matter in application No. 656,857, filed August 11, 1923 and issued as Patent #1,567,599, dated December 29, 1925, only so much of the mechanism shown in said patent has been here disclosed as will be necessary for a complete understanding of the present invention. Accordingly reference characters applied to like parts in the present case are the same as the characters applied to the same parts in the aforementioned patent, which patent may be readily referred to for a full understanding of the various details of the selector and printing mechanisms not herein fully set forth.

The selector bars 59 to 63 and the shift control bar 501 shown in Figure 1 may be controlled mechanically by a single selector magnet as set forth in the above mentioned patent, or may be controlled by selector magnets individual thereto from a rotary distributor in either a multiplex or a start-stop signal printing telegraph system in any manner well known to the art.

The type bar action comprising the actuating bars 108, arms 113, type bars 116 and the action of the printing bail parts 125 to 129, the action of the spacing mechanism controlled by the parts 166 to 169, and the ribbon feeding actuating mechanisms, and the various other printing actions will be fully understood by referring to the above mentioned patent.

The mechanism related to the present invention comprises platen block 488 mounted on a head 489 which is mounted slidably in a guide bracket secured to frame 400. An extension 491 of member 489 is pivotally linked to a rocker arm 492 which is pivotally supported from frame 400 at 493. Ribbon shift pivot 318 is secured to and movable with an extension 494 of arm 492. A spring 595 connected to arm 492 tends to throw arm 492 with 488 and 489 forward into shifted position. Block 488 is just wide enough to be positioned under one of the characters carried by type bars 116 as shown in Figure 1. Secured to head 489 are a plurality of members 495, which, as the head is moved in the shift operation, are arranged to depress the edges of the tape in order to insure contact with the tape of only the one character under which block 488 has been interposed. It will be seen that according to the position of arm 492 either an upper or lower case character will be printed, and the ribbon will be properly shifted by the movement of extension 494.

A pin 496, secured to 492, is in slidable engagement with a slot in the end of a shift operating member 497, member 497 is pivoted at a point 498 and urged to the right in Figure 1 by a spring 499, to maintain a cam projec-

tion 500 thereon, against bar 125 of the printer bail operating frame. A special shift control bar 501 is added to notched selector bars 59 to 63, and an extra cam, selector finger and latch, are added to the selector cam shaft 70 shown in the copending application to control this bar by a line impulse in the same manner as the selector bars 59 to 63 are controlled. The signal periods, when this bar is added in a start-stop printing system will be made up of eight intervals; namely, a start interval, 75 five selector bar control intervals, a shift control interval, and a stop interval. The transmitter will be arranged to transmit a marking condition in the shift control interval 80 when block 488 is to be shifted to print an upper case figure, and to transmit a spacing condition when block 488 is to remain in the letter printing position. The selector cams will of course be spaced accordingly, in proper 85 angular and axial position.

A stop projection 502 is carried by bar 501 in such a position that it will be directly beneath the end of shift control bar 497 when bar 501 is in unactuated position, and a wide slot is cut directly beneath bar 497 in all the notched selector bars so that bar 497 can move into these wide slots with the selector bars either in actuated or unactuated position. When a marking impulse is received during the shift control interval, bar 501 will be permitted to move to the left in Figure 3 under the influence of its spring 65, and as the printing bail moves upward, bar 497 will rock on its pivot 498 under the influence of spring 499 with cam projection 500 in engagement with bar 125, and will move into the wide selector bar slots. The actuating bar 108 selected by the arrangement of the notched bars will also be moved into its aligned slots. When the two bars have reached the bottoms of their respective slots, bar 497 will have moved to a position which will have caused arm 492 to be moved by spring 595 to shift block 488 into its forward or upper case position. The printing stroke of the selected type bar will then commence and there will be no further movement of bar 497 until the printing has been effected and the selected type bar has returned to normal. Then the return or downward movement of the printer bail frame will cam the selected actuating bar 108 and bar 497 out of the aligned slots. As soon as the bars 108 and 497 have been lifted clear of the notched selector bars, member 77 is actuated by cam 90 to restore the selector bars and the shift control bar 501 to unactuated position, when stop projection 502 will again be positioned under bar 497. Until another code combination, with a marking impulse in the seventh interval is received, bar 501 will be locked in the position shown in Figure 3 by its control finger, and platen block 488 will 130

be held to the rear or in lower case position as shown in Figure 1.

In Figure 5 a modified form of the invention is disclosed in which the platen and platen carriage construction shown in Figure 3 of said Patent #1,567,599 is modified. The platen construction and the carriage are the same as shown in said patent and the tape together with the platen is shifted bodily. A shift control member 503 suitably pivoted on a point 504 to the frame (not shown) has the upper end thereof normally held against the projection 502 of the shift control bar 501. An actuating projection 506 formed on member 503 is urged into engagement with the printed operating bail member 125 by the spring 505. Pivotedly secured to the lower end of the member 503 by means of pin 507 is a shift control latch member 508. Member 508 is provided with extension 509 normally held in engagement with an edge of the member 503 by means of helical spring 510 which may be coiled around and supported on an extension of the pin 507 (not shown). A carriage shift bell crank member 511 is pivotally supported from the frame by means of a pin 512 and is normally urged counter-clockwise by the spring 513, until a projection 514 thereof engages the end of the latch member 508. Pivotally secured to the end of one arm of the bell crank member 511 by means of pin 515 is a link 516. Link 516 is provided with a guide slot 517 adjacent the upper end thereof through which the guide pin 518 extends. Guide pin 518 is suitably secured in the supporting framework and guides and limits member 516 in a reciprocating motion. The upper end of member 516 is adapted to be engaged by the lower surface of the printer actuating bail member 128. Formed on the other arm of the bell crank member 511 are the extensions 519 between which a pin 520 is positioned. Pin 520 is secured to the member 420 of the platen carriage.

Secured to the member 420 are the ribbon shifting elements 319 and 324, which shift the ribbon in position for printing when the carriage is shifted as will more fully appear by a reference to the said Patent 1,567,599.

As set forth in the copending application projection 415 to the member 420 is adapted to engage the stop screws 442 and 443 and will limit the travel of the carriage. Supported from the member 420 is a carriage positioning roller or member 521 which is adapted to ride over the projection 522 of the limiting member 523. Member 523 is pivotally mounted and urged preferably by a spring (not shown) into yielding engagement with the roller or member 521.

In operation of this form of the invention the parts are normally positioned as shown and the platen together with the tape (not shown) will be positioned to receive print-

ing impressions of the selected type bars in lower case or unshifted position. As the printing bail structure moves to effect printing strokes in a manner more fully set forth in the said Patent #1,567,599, the stop 514 will engage the end of latch member 508 and motion of the bell crank member 511 under influence of spring 513 will be prevented. When, however, a character in the upper case is selected the shift control bar 501 will be actuated and will shift the projection 502 from beneath the end of the member 503. As the printing bail moves in its printing stroke, spring 505 will shift member 503 clockwise about its pivot 504 under control of the printing bail member 125, and the cam projection 506 and the end of latch 508 will be shifted to the left in Figure 5 until it is disengaged from the stop member 514. As soon as this disengagement occurs spring 513 will shift the bell crank member counter-clockwise and the right extension thereof will engage the pin 520 and will shift the member 420 together with the platen and tape into the upper case or shifted position. The parts are so proportioned and arranged that the movement of the platen into the shifted position will be completed before a printing impact of the selected type bar is effected. After the printing of the selected character has been effected the printing bail structure will be returned, as more fully set forth in said Patent 1,567,599, and the selected type bar will return to unactuated position. As the printing bail structure returns to normal and moves the member 128 downward the side of member 128 will engage the end of link 516 and will force the bell crank 511 in a clockwise direction. At the same time bar 125 will move the member 503 until the end of latch 508 drops behind the projection 514 and projection 502 of the bar 501 is moved to the position shown in Figure 5. During the return movement of the printing bail structure, member 125 will engage the cam projection 506 of member 503 and will force the end of the member 503 out of the aligned selector bar slots. During this motion of the member 503 the end of the latch 508 will engage the left side or edge of the projection 514 and the latch 508 will move about pin 507 as a pivot until the return movement of the printer bail permits spring 510 to force the latch 508 into position shown in Figure 5. When this occurs the parts will be locked with the platen and tape in unshifted or lower case position. In the form shown in Figure 6, a further modification of the invention is shown in which the carriage is moved to the upper case or shifted position by means of a cam member and is restored by means of a spring. In this form the shift actuating bar of the said Patent 1,567,599 together with the cam extension 433 thereof and the carriage ac-

tuating rollers 431 and 436 are retained as set forth in the copending application. The carriage together with the platen and tape as shown in Figure 3 of said Patent 1,567,599 5 is normally held by means of a spring 524 secured thereto and to an extension 525 of a spring-post with the roller 436 carried by the member 420 in engagement with the cam extension 433. When a selected character 10 is to be printed in the lower case position the projection 502 of the bar 501 prevents motion of the shift actuating bar 108 into the aligned slots and the platen will remain in the position shown in Figure 6, as printing 15 of the selected character is effected. When, however, the character is to be printed in the upper case or shifted position, in addition to selection of the type bar carrying the character to be printed the bar 501 is selected and the shift control bar 108 will move 20 into the aligned slots as the printing bail moves in its printing stroke. As the bail moves in its printing stroke cam member 433 will be shifted vertically and will force 25 the carriage together with the platen and tape into position to receive the upper case or shifted character impression just before the printing impact of the selected tape bar. As the parts restore to normal spring 435 30 will move the shift actuating bar downward and spring 524 will effect the return of the platen carriage to normal or unshifted position as shown in Figure 6.

In the forms of the invention so far described the shift mechanism automatically restores to normal position after each shift movement, and must be moved from normal position each time a character is to be printed in the shifted position. This introduces unnecessary movement in the mechanism when successive characters in the shifted position are to be transmitted. In the preferred embodiments of the invention hereinafter set forth, the shift mechanism will remain in a given case position until a different position is required for the printing of a succeeding character.

In the form of invention shown in Figures 7 and 8, a preferred embodiment is disclosed 50 in which the shift mechanism is mechanically actuated, and the platen remains in one position until a character is to be printed in a different case position. In this form of the invention the platen 488 and the platen block 489 are supported on and slidable on the member 490 as set forth in connection with Figure 1, and the tape feeding and supporting means in this form of the invention are the same as are shown in Figure 1 to which a 55 reference may be had for a full understanding of the parts. Platen block 489 is formed integrally with or rigidly secured to the actuating extension 547 to which the ribbon shifting parts are connected at 318. The rear end 60 of the actuating extension 547 is pivotally

connected by means of pin 549 to one end of supporting link or member 550 which at its other end is pivoted at 551 to the frame 400 of the printer. Rotatably supported on the pin 549 at opposite sides of the extension 547 are shift and unshift rollers 552. The shift roller 552 in the Figure 7 engages an edge of the cam extension 553 of shift actuating bar 554. The opposite edge of the cam extension 553 reacts against a roller 555 which is pivotally supported on an extension of the frame 400. Suitably supported from the frame 400 is an unshift reacting roller or member 556, against which one edge of the unshift cam extension 557 of the unshift actuating bar 558 is held by means of spring 559. Shift and unshift actuating bars 554 and 558 are provided with cam projections 110 and actuating shoulders 111 such as are provided on actuating bars 108. Shoulders 111 are adapted to be engaged by the printing bail 128, and cam projections 110 held in engagement with the bar 125 of the printing bail structure by means of the springs 560.

Shift control selector bar 501 is provided with a projection 561 which in the unactuated or unselected position of the bar 501 prevents movement of shift actuating bar 554 to the right in Figure 7 into the aligned slots 562 of the selector bars 59 to 63 and the actuated or selected position of bar 501 permits movement of actuating bar 554 into the aligned slots 562 during a printing stroke of the bail structure. Bar 501 is also provided with a projection 563 which in the selected or actuated position of the bar 501 is positioned beneath the unshift bar 558 and prevents movement thereof into the aligned slots 564 of the bars 59 to 63 during a printing stroke of the bail structure and in the unactuated or unselected position of the bar 501 the unshift bar 558 is permitted to move into the aligned slots 564 of the bars 59 to 63. In order to insure the proper positioning of the platen 488 in the shifted or unshifted position a bell crank member 565 suitably supported from the frame 400 on a pivot 566 is provided with a triangular projection 567 which is forced into engagement with one of the rollers 552 by means of a spring 568. Projection 567 is so proportioned with relation to the roller 552 that the platen will be yieldingly held in either case position by the action of spring 568, which is of sufficient strength to hold the parts properly in either case position but permits shifting of the parts under the influence of the cam members 553 and 557.

In operation of this form of invention when a character is to be printed in the unshifted or normal position, the selection is set up on the selector bars 59 to 63 as above set forth and shift control selector bar 501 will remain in unactuated position with the projection 561 positioned beneath the shift actuating bar 554. After the selection has

been set up on the selector bars, the printing mechanism is tripped and the bail structure moves upward in a printing stroke, permitting the selected actuating bar 108 and the unshift bar 558 to move into the aligned slots. As the movement of the printing bail structure continues the bar 128 will engage the shoulder 111 of the selected actuating bar 108 and the unshift bar 554, causing a printing stroke of the selected type bar and an upward movement of the cam extension 557. If the platen is in unshifted position, the upward movement of the bar 554 will have no effect. However, if the parts are in shifted position, the upward movement of the cam extension 557 will move between the roller 556 and the unshift roller 552 and will force the extension 547 and the platen block 489 to the right in Figure 7 before a printing impact of the selected character occurs. So long as the characters received are to be printed in the shifted position of the parts, bar 501 will be selected and will move to the position shown in Figure 8. In this position of the parts, extension 561 will be moved out of alignment will shift actuating bar 554, and projection 563 will be positioned in alignment with unshift actuating bar 558. As the printing bail structure moves in a printing stroke unshift actuating bar 554 and the selected actuating bar 108 will move into the aligned slots in the selector bars 59 to 63, and will then be moved across the aligned slots by the bail 128. This effects a printing stroke of the selected type bar and an upward movement of the cam extension 553 which forces the extension 547 forward positioning the platen 488 in shifted position. Platen 488 will remain in shifted position until the selector bar 501 is positioned in unselected or unactuated position for the printing of the character to prevent actuation of bar 554 and causing actuation of the unshift bar 558. The parts will then be restored to the position shown in Figure 7 and will remain until another character is to be printed in the shifted position of the platen.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:—

1. In a printing telegraph receiver, a plurality of characters to be recorded; means for recording said characters in offset lines; a permutation device adapted to control both the character to be recorded and the line in

which the record is to be made; and solely mechanical connections between said permutation device and said means.

2. In a printing telegraph receiver; a plurality of characters; a platen cooperating with said characters to effect printing thereof; a plurality of elements adapted to be set in varying permutations; means controlled by said elements to bring two of said characters to printing position simultaneously; means to bring said platen in printing relation to a selected character; and entirely mechanical connections between said means and said elements. 70 75

3. In a register device, a plurality of groups of characters; permutation mechanism in said register device responsive to code combinations of conditions for simultaneously selecting a character in each of said groups; mechanism responsive to a condition accompanying each of said code combination of conditions for effecting registration of one of said selected characters; and solely mechanical connections interposed between mechanisms. 80 85 90

4. In a printing telegraph receiver, a plurality of characters arranged in groups; permutation means responsive to received code combinations of signalling conditions for selecting one of said characters for printing; and solely mechanical means controlled by said permutation means to print the selected characters of one of said groups in offset relation with respect to characters in another of said groups. 95 100

5. In a receiver, a plurality of groups of characters, permutation mechanism in said receiver responsive to the received code combinations of signalling conditions for simultaneously selecting a character in each of said groups, shift mechanism; an added permutation device responsive to a signalling condition added to each code combination of conditions for variably operating said shift mechanism to effect recording of one of said simultaneously selected characters; and solely mechanical connections between said shift mechanism and said permutation device. 105 110

6. In combination, a receiving device comprising a plurality of characters arranged in groups; permutation means in said receiving device responsive to received code combinations of signalling conditions for simultaneously selecting a character in each of said groups; a device controlled by said permutation means in response to a signalling condition accompanying each code combination of conditions; and mechanism controlled by said device through solely mechanical connections for effecting recording of one of said selected characters. 115 120

7. In a printing telegraph receiver, a plurality of groups of characters; permutation means responsive to received code combina- 130

- tions of signalling conditions for selecting a character in each of said groups; a further permutation means responsive to a signalling condition accompanying each code combination of conditions for determining which of said selected characters is to be printed; means to print the selected characters of one group in offset relation with respect to the selected characters of another group; and solely mechanical connections interposed between said permutation means and said last mentioned means.

8. In a printing receiver, a plurality of groups of characters; permutation means responsive to received code combinations of selecting conditions for selecting a character in each of said groups; permutation means in addition to said first mentioned permutation means responsive to a signalling condition accompanying each code combination for selecting between said groups of characters; a tape; means for printing said selected characters on said tape in a manner indicative of the group from which said character has been selected; and solely mechanical connections controlled by said additional permutation means controlling said last mentioned means.

9. In a printing telegraph receiver; a plurality of groups of characters; a tape; permutation means responsive to received code combinations of signalling conditions for simultaneously selecting a character in each of said groups; permutation means responsive to a signalling condition accompanying each code combination for selecting one of said groups; means for printing a selected character of the selected group on said tape in a manner that indicates the group from which printing occurs independently of the particular character; and solely mechanical connections interposed between permutation means and said last mentioned means.

10. In a printing telegraph receiver, a plurality of type bars; a platen arranged to coat with said type bars and provided with shift and unshift position; means responsive to code combinations of received impulse conditions for selecting one of said type bars for operation; and solely mechanical means including a pivoted shift bar responsive to an extra impulse accompanying said code combination for positioning said platen to shift and unshift position.

11. In a printing telegraph receiver, a printing mechanism comprising a plurality of groups of characters; a shift mechanism held in a first position by means of a spring to permit printing of the characters in one of said groups; means controlled by said printing mechanism for moving said shift mechanism to a second position against the tension of said spring to permit the printing of characters in another of said groups; said shift mechanism including a selectable shift bar adapted to cooperate with said printing

mechanism for normally holding said shifting mechanism in said second position; selecting mechanism comprising a plurality of notched permutation members responsive to received code combinations of selecting conditions controlling said printing mechanism and responsive to a selecting condition added to each code combination for controlling said shift bar.

12. In a printing telegraph receiver, a printing mechanism comprising a plurality of groups of characters; a shift mechanism held in a first position by means of a spring to cause printing of the characters in one of said groups; means controlled by said printing mechanism for moving said shift mechanism against the tension of said spring to a second position to print characters in another of said groups; a selectable shift control bar for normally holding said shifting mechanism in said second position; and means responsive to code combinations of received impulses for controlling said printing mechanisms and means responsive to an extra impulse for controlling said shift bar; said shift bar being provided with a yieldable end adapted to coact with said shift mechanism to permit the restoration of said shift bar to its unselected position prior to the movement of said shift mechanism to said second position.

13. In a printing telegraph receiver, a printing mechanism comprising a plurality of groups of characters; a shift mechanism normally held by means of a spring in position to cause printing of the characters in one of said groups; means comprising a cam member for moving said shift mechanism against the tension of said spring to print characters in another of said groups; and selecting mechanism comprising a plurality of notched selector bars responsive to received code combinations of selecting conditions controlling said printing mechanism and responsive to a selecting condition added to each code combination for controlling said cam member.

14. A printing telegraph machine comprising a selecting mechanism; a printing mechanism controlled by said selecting mechanism; actuating means for said printing mechanism; a shift mechanism coacting with said printing mechanism and normally spring held in unshift position; means comprising a cam member to force said shift mechanism against the tension of said spring into shifted position, said last mentioned means being controlled by said selecting mechanism and operated by said actuating means.

15. In a printing telegraph receiver, selecting mechanism responsive to code combinations of received impulses; printing mechanism comprising a plurality of sets of characters controlled by said selecting mechanism; a platen coacting with said printing

mechanism; a movable carriage spring held in a normal position upon which said platen is mounted; and a cam member controlled by an impulse added to certain of said code combinations and adapted to force said carriage against the tension of said spring into an alternate position.

16. In a printing telegraph receiver, a plurality of type bars; a platen arranged to co-act with said type bars and operable to shift and unshift position; means responsive to code combinations of received conditions for selecting one of said type bars; and solely mechanical means including a selectable cam member responsive to an added condition for moving said platen to shift or unshift position.

17. In a printing telegraph receiver, a plurality of character elements, a shift control lever and notched permutation means responsive to code combinations of impulses for selectively operating said character elements and said shift lever.

18. In a printing telegraph receiver, a plurality of character elements; a plurality of permutation members responsive to code combinations of signalling conditions for selecting said character elements; a shift control code bar selectively operated by a single signalling condition accompanying said code combinations of conditions; and a shift bar controlled by said shift code bar for operating the shift character selected.

19. A printing telegraph receiver comprising a selecting mechanism embodying a plurality of notched permutation members responsive to code combinations of uniform marking conditions and uniform spacing conditions; printing means embodying a plurality of groups of characters, each group being selectable by a different code combination; a shift mechanism for determining the character of a selected group to be printed; and a shift control code bar responsive to a special shift selecting condition added to said code combinations controlling said shift mechanism.

20. In a printing telegraph machine, a selector mechanism responsive to code combinations of selecting conditions; a shift mechanism having a shift and unshift position; a cam member to move said shift mechanism to shifted position; a cam member to restore said shift mechanism to unshifted position; and means selectively controlled by an added condition accompanying said code combinations of selecting conditions selectively controlling said cam members.

21. In a printing telegraph receiver; printing means comprising a plurality of groups of characters; a shift mechanism normally latched in position against the tension of a spring to cause printing of characters in one of said groups; selectively controlled means for releasing said shift mechanism to move to

a position to cause printing of another of said groups of characters; and means for restoring said shift mechanism to latched position after each movement from said first mentioned to said second mentioned position.

22. The combination as set forth in claim 21 in which said shift mechanism comprises a common selectable member controlling the release and the restoration thereof.

23. The combination as set forth in claim 21 in which said shift mechanism comprises a selectable member controlling the release thereof; and means independent of said selectable member for restoring said shift mechanism.

24. A printing telegraph receiver comprising a printing mechanism embodying a plurality of character elements selectable in groups; shift mechanism for determining the character of a selected group to be printed; selecting means responsive to code combinations of uniform marking and uniform spacing conditions for selecting said groups and responsive to a shift control condition added to said code combinations to control said shift mechanism; and means for preventing the actuation of said shift mechanism until a changed position thereof is required for a succeeding printing operation.

25. In a receiving register; registering mechanism comprising a plurality of groups of characters; a shift mechanism normally held in position to cause registration of the characters in one of said groups by means of a spring; means for moving said shift mechanism against the tension of said spring to register characters in another of said groups; and permutation selecting means responsive to received code combinations of selecting conditions controlling said registering mechanism, and comprising a shift control selector bar responsive to a selecting condition added to each code combination controlling said first mentioned means.

26. In a printing telegraph receiver, a plurality of character elements; a shift mechanism normally locked in unshift position; and means responsive to code combinations of impulses for selectively operating said character elements and releasing said shift mechanism for movement to shift position.

27. In a printing telegraph receiver; a plurality of type characters; a shift mechanism; means responsive to a code combination of impulses for selecting one of said type bars for operation and simultaneously conditioning said shift mechanism for operation; and means for operating said selected type character and releasing said shift mechanism for operation.

28. In a printing telegraph receiver, a plurality of character elements; a platen; a ribbon; a shift bar; and means controlled by said shift bar for simultaneously shifting said platen and said ribbon; and means for

simultaneously selecting one of said character elements.

29. In a printing telegraph receiver, a normally latched shift mechanism selectively controlled by an extra impulse following a code combination of impulses; a printing bail; means for releasing mechanism for operation upon movement of said printing bail to print; and means controlled by said printing bail upon its return to normal for latching said shift mechanism.

30. In a printing telegraph receiver, a shift mechanism normally latched in unshift position; a shift control bar being selectively responsive to an impulse following a code combination of impulses latching said shifting mechanism from operation; a printing bail for controlling said shift control bar to unlatch said shift mechanism; and means controlled by said printing bail for restoring said shift control bar and positioning said shift mechanism to be again latched by said shift control bar.

31. In a printing telegraph receiver, a plurality of type character elements; a latched shift control mechanism; means responsive to code combinations of impulses for selecting one of said character elements for operation; a printing bail; means controlled upon operating movement of said printing bail for releasing said shift mechanism for operation and for operating said selected character element; and means controlled by said printing bail upon its return to normal for again latching said shift mechanism in unshift position.

32. In a printing telegraph receiver, a member carrying type characters in two different rows, a platen arranged to coact with said member and operable into two positions, means responsive to a code combination of impulses received for selecting for printing two characters carried by said member, and solely mechanical means operated as determined by one unit of said code combination of impulses for positioning said platen to print one of said selected characters.

33. In a printing telegraph receiver, a member carrying type characters in two different rows, a plurality of selecting elements responsive in accordance with an equal length letter code for operating said member to position two type characters in a printing position, a platen, and an additional selecting element responsive to one unit of said code for effecting solely mechanically a relative movement between said member and said platen to permit the printing of one of said selected characters.

34. In a printing telegraph receiver, a member carrying type characters in two different rows, means responsive to an equal length letter code for operating said member to position two of the type characters in a printing position, a platen, and means re-

sponsive to one unit of said code for effecting solely mechanically a relative movement between said member and said platen to permit the printing of one of the selected characters.

35. In a printing telegraph receiver, a type member carrying a plurality of characters in offset relation, means responsive to an equal length letter code for selecting at least two of said characters for printing, a platen, and means responsive to one unit of said equal length letter code for determining solely mechanically the position of said platen and the printing of one of the selected characters.

36. In a printing telegraph receiver, a series of elements divided into two groups, all of the elements in each group having a characteristic peculiar to the group, a series of permutation members, each permutation acting to select simultaneously an element of each group, and an additional permutation member cooperating with said series for acting as the sole control to select the group.

In testimony whereof I affix my signature. 90
EDWARD E. KLEINSCHMIDT.
